CATALYTIC REFORMING PROCESS AND PRE-TREATMENT OF FEED STOCK

Jesse M. Brooke, Sweeny, Tex., and Forest E. Gilmore, Bartlesville, Okla., assignors to Phillips Petroleum Company, a corporation of Delaware

Application May 28, 1956, Serial No. 587,556

18 Claims. (Cl. 208—91)

This invention relates to an improved catalytic reforming and sulfur removal process.

The catalytic reforming of gasoline-boiling-range hydrocarbons to improve their antiknock quality is a well developed commercial process. A great many available feed stocks for catalytic reforming contain deleterious amounts of sulfur and it is common practice to subject the feed stock to a desulfurizing treatment prior to passing the feed to a catalytic reforming zone. A common catalyst for use in reforming processes comprises platinum in concentrations of 0.1 to 2 or 3 percent on a suitable porous support or carrier, such as silica-alumina or alumina which may contain a small concentration of combined fluorine. Various other well known reforming catalysts are commercially available for reforming processes. A feed to be treated is contacted with the catalyst in admixture with free hydrogen under substantial pressure and at an elevated temperature controlled to provide the desired reformation of the feed stock. It has been discovered that in many commercial reforming processes, even where the feed stock is desulfurized before being passed to the reforming zone, an excessive amount of corrosion has been occurring in the iron equipment which is contacted with the feed at high temperatures. This is particularly true in the charge pre-heater furnace upstream of the catalytic reactor where losses of as much as 0.04 inch of metal were experienced in a 6 months period under normal operating conditions. This is found to be common experience with catalytic reformers and is so serious that the National Association of Corrosion Engineers has delegated a special committee to investigate the problem.

This invention is concerned with a practical solution of the corrosion problem in a catalytic reforming process as applied to gasoline-boiling-range hydrocarbon feed stocks containing minor but deleterious amounts of sulfur.

It is an object of the invention to provide a process for reforming gasoline-boiling-range hydrocarbons containing minor but deleterious amounts of sulfur. Another object is to provide a method of reducing corrosion of equipment in a catalytic reforming process due to sulfur present in the feed. A further object is to provide a method of reducing the sulfur content of a hydrocarbon feed stock so as to render the same substantially non-corrosive at high temperatures. Other objects of the invention will become apparent from consideration of the accompanying disclosure.

In order to provide a clear understanding of the invention, reference is made to the accompanying schematic drawing which shows a flow of a reforming process in accordance with the invention. A suitable charge stock comprising a gasoline-boiling-range hydrocarbon fraction, such as a straight run fraction from a crude distillation unit, is passed via line 10 to a desulfurizing zone 12 where it is contacted with a desulfurizing agent such as pelleted montmorillonite, an aluminum silicate clay.

2

Other desulfurizing agents include bauxite, synthetic aluminas, etc. The partially desulfurized effluent is passed via line 14 to fractionator 18 for removal of a heart cut to be fed by the reformer. In some instances 5 it is desirable to also pass the charge stock thru an additional treating zone such as zone 16 in which the charge stock is contacted with a caustic or amine treating solution which is effective in sulfur removal. In fractionation zone 18 light hydrocarbon material formed in 10 the desulfurizing step and/or present in the original charge stock, together with H_2S and water present in the feed or resulting from the desulfurizing step, are taken overhead thru line 20. Heavy hydrocarbons not suitable for the reforming step are removed via line 22 15 and may be charged to a catalytic cracking zone or to other use as desired. The heart cut from fractionator 18 is pumped via line 24 by pump 25 thru heater 27 to a second desulfurizing zone 26 where the partially desulfurized feed is contacted with a readily sulfidable or sulfur-accepting metal under sulfiding conditions so as to 20 further deplete the sulfur content of the feed. The sulfur-denuded feed is then passed via line 28 to preheater 30 where the same is raised to the desired reaction temperature prior to introduction via line 32 into catalytic 25 reformer 34. Reformate is passed via line 36 thru a separation zone 38 in which a hydrogen-containing stream is separated and recovered in line 42 from which it is recycled in line 48 to line 24 upstream of sulfur removal zone 26. Net hydrogen is recovered from line 49. Compressor 46 in line 48 is utilized to boost the hydrogen pressure sufficient to permit introduction to line 24. The reformate is recovered from separator 38 in line 40 thru 30 which it is passed to further processing as desired.

It is in a catalytic reforming plant such as that shown 35 in the drawing, with the exception of desulfurizing zone 26 and the recycle of the hydrogen thru this desulfurizing zone, that we have observed excessive and intolerable corrosion of the equipment particularly in charge pre-heating zone 30. This is surprising because of the fact 40 that substantial sulfur removal from the charge stock has been effected so that the charge stock is considered substantially "sweet." It is believed that one probable cause of corrosion is the buildup of sulfur in the hydrogen recycle stream. The minor quantities of sulfur in 45 the charge stock passed to the catalytic reformer substantially all appear in the form of H_2S in the hydrogen recycle stream and by continually recycling hydrogen the H_2S -content of the recycle stream and consequently 50 of the charge stream to the preheater and reformer increases to the point where the net effect is excessive corrosion, particularly in heating zone 30 where the hot feed stream has the first opportunity to attack the metal tubing.

In accordance with the invention, a final sulfur removal step is effected on the charge stock just prior to 55 its introduction to the charge preheater (zone 30). This sulfur removal step comprises contacting the feed with a sulfur-accepting metal under metal sulfiding conditions so as to substantially reduce the residual content 60 of the charge stock to a low level which is not unduly corrosive to metal conduits downstream of the desulfurizer. The hydrogen recycle stream containing substantially all of the sulfur in the effluent from the catalytic reforming zone is recycled to the final desulfurizer along 65 with the charge stock (or separately) so that the H_2S content of the hydrogen recycle stream does not build up.

Metals which are suitable for the sulfur removal step in zone 26 include iron, copper, and silver. Iron is effective when utilized in particulate form such as shavings and cuttings obtained from machine shops or in the form of iron filings or reduced iron powder. Copper can be utilized in similar form. It is also feasible to distend

copper and/or silver on refractory porous support material such as bauxite or other porous alumina by methods well known in the art.

In operation of the process, two or more vessels such as vessel 26 are manifolded together in known manner so that while one is on-stream effecting sulfur removal, another is being regenerated. Regeneration of the particulate iron is effected by burning a suitable fuel gas with excess oxygen inside vessel 26 so as to convert the iron sulfide formed during the sulfur removal step to iron oxide thereby releasing H_2S into flue gases. After substantially all of the iron sulfide has been converted to iron oxide, hot hydrogen gas is passed thru the hot iron oxide particles so as to reduce the iron oxide to iron. It is also possible to utilize the iron oxide for sulfur removal inasmuch as H_2S reacts with iron oxide to produce iron sulfide and water but this is not desirable since water is deleterious in the reforming zone. When utilizing copper or silver in the form of turnings, millings, shavings, or other particulate form, or deposited or distended on porous refractory material, as is preferable with silver for reasons of economy, the regeneration is preferably effected by merely contacting the sulfided metal with hot hydrogen thereby forming H_2S which passes off in the effluent gas. Usually the compressor discharge hydrogen (compressor 46) is hot enough to effect the regeneration and can be removed via line 50 and passed to the particular vessel 26 being regenerated at any given time. In instances where the temperature of the compressed hydrogen is insufficient to be used in the regeneration step additional heat may be readily added in well known manner. A relatively small amount of H_2 is required and it may be more feasible to heat the treater material by means of a fire inside the treater before introducing the H_2 .

It might be well to note that copper and silver react rapidly with sulfur compounds in petroleum in 500 to 600° F., which indicates the preferred range of temperature to be utilized when desulfurizing with these metals. Copper sulfide reacts with hydrogen to produce H_2S at about 1600° F. so that a temperature of this order is sufficient to restore or regenerate the copper treating agent. Silver sulfide reacts with hydrogen to produce H_2S at 750 to 850° F. and regeneration in this range is likewise preferred when utilizing silver as the treating agent. Since copper and silver sulfides react readily with steam to produce the oxides and copper and silver oxides react with hydrogen at 600° F. to produce the metals, this regeneration route is also feasible.

In order to illustrate the invention the following data are presented but are not to be interpreted as unnecessarily limiting the invention. A charge stock having a boiling range of 151 to 402° F. and an API @ 60° F./60° F. of 55.2 and containing 0.187 weight percent sulfur is fed via line 10 to desulfurizing zone 12 packed with porous bauxite where it is treated in known manner to reduce the sulfur content of the charge in line 24 to 0.010 weight percent. The effluent is fractionated in fractionator 18 so as to remove overhead light hydrocarbons, H_2S , and H_2O and a minor heavy hydrocarbon bottoms fraction, thereby recovering a heart cut (line 24) having a boiling range of 210 to 380° F. an API @ 60° F./60° F. of 53.6. The temperature of the partially desulfurized stream is raised in heater 27 to 600° F. and is then passed into desulfurizing zone 26 together with hydrogen recycle from line 48 where the sulfur content is reduced to 0.002 weight percent by contacting the feed with copper turnings. The low sulfur content charge stock is then passed via line 28 to heating zone 30 where the temperature is raised to about 880° F. which is the temperature maintained in reactor 34 along with a pressure of 560 p.s.i.a. The hydrogen-to-oil mol ratio in reactor 34 is maintained at about 8 to 1 with an hourly space velocity of approximately 3 barrels of oil per hour per barrel of catalyst using commercial platinum reform-

ing catalyst. The hydrogen sulfide concentration in the recycle stream in line 48 amounts to 0.01 grain per 100 s.c.f. In conventional operation without sulfur removal in zone 28 the hydrogen sulfide concentration in the hydrogen recycle line runs between 0.5 and 10 grains per 100 s.c.f. depending upon the sulfur content of the feed stock and the percent of removal of sulfur in zones 12 and/or 16. In this type of operation in accordance with the invention corrosion of the apparatus in preheater 30 and reactor 34 is substantially negligible.

In regenerating the copper turnings in vessel 26, hydrogen from line 50 is heated in a conventional indirect heat exchanger to a temperature of about 1600° F. and is passed into alternate vessel 26 (offstream) so as to contact the copper sulfide and convert the same to metallic copper.

Normally, the initial sulfur removal step removes at least 80 and up to 90 or more percent of the sulfur from the feed stock, while at least 65 and, preferably, 70 or more percent of the remaining sulfur in the feed is removed in the sulfur removal step just preceding the preheating of the feed to reactor temperature. Since separation zone 38 is maintained at relatively high pressures, such as about 450 p.s.i.a., only a small amount of compression is required in line 48 in order to reintroduce the recycled hydrogen stream to the feed stream in line 24 where the pressure is only about 600 p.s.i.a., requiring a recycle pressure in line 48 downstream of compressor 46 in the neighborhood of 613 p.s.i.a. A significant advantage of the invention resides in the fact that the feed stream is depleted of most of the sulfur content at low pressure in the absence of hydrogen which, of course, is more economical than treatment at higher pressure and the high pressure treatment with hot metal is positioned in line 24 below pump or compressor 25 where high pressure is conventionally maintained thereby avoiding a special compression step. Another advantage lies in the fact that bauxite and caustic treatment are more economical when applied to sulfur removal from streams in which the sulfur concentration is relatively high than sulfur removal by contact with hot metal but the latter is more effective in removing lower concentrations of sulfur. The process of the invention is particularly applicable to the treatment of feed stocks containing at least 0.05 weight percent sulfur and the sulfur content is usually reduced to below 0.003 weight percent by the process of the invention.

Certain modifications of the invention will become apparent to those skilled in the art and the illustrative details disclosed are not to be construed as imposing unnecessary limitations on the invention.

We claim:

1. A process for reforming a gasoline boiling range hydrocarbon stock containing at least 0.05 weight percent sulfur, which comprises contacting said stock in a first desulfurizing zone with a solid particulate desulfurizing agent so as to remove the major portion of said sulfur; fractionating the partially desulfurized stock so as to remove at least the lighter components, including H_2S ; contacting the remaining stock with a sulfur-accepting metal in a second desulfurizing zone under metal sulfide-forming conditions including a temperature of at least 500° F. so as to remove the major portion of the remaining sulfur and reduce the sulfur content below 0.003 weight percent; and passing the resulting stock to a catalytic reforming zone in contact with a reforming catalyst maintained under reforming conditions including a substantial amount of free hydrogen to produce a suitable reformate.
2. The process of claim 1 including the step of recovering a hydrogen-containing stream from said reformate including a minor amount of H_2S and recycling same to said second desulfurizing zone.
3. The process of claim 1 wherein the metal sulfide formed in said second desulfurizing zone is periodically

regenerated by oxidation and then reduction with hydrogen.

4. The process of claim 3 wherein said metal comprises particulate iron.

5. The process of claim 1 wherein said metal comprises copper and the resulting copper sulfide is periodically regenerated by reduction with hot hydrogen at a temperature of at least 600° F.

6. The process of claim 1 wherein said metal comprises silver and the resulting silver sulfide is periodically regenerated by reduction with hot hydrogen at a temperature in the range of 750° to 850° F.

7. A process for reforming a gasoline boiling range hydrocarbon stock containing at least 0.05 weight percent sulfur, comprising the steps of contacting said stock in a first desulfurizing zone with a solid, particulate desulfurizing agent and removing light ends including H₂S from the effluent so as to reduce the sulfur content to below 0.010 weight percent; passing the resulting stock to a second desulfurizing zone in contact with a sulfidable metal at a temperature of at least 500° F. and in the presence of recycled hydrogen so as to form metal sulfide and reduce the sulfur content of said stock to below 0.003 weight percent; thereafter heating the resulting stock to reforming temperature; reforming the heated stock in admixture with desulfurized hydrogen in contact with a platinum reforming catalyst under reforming conditions so as to produce an improved reformate; recovering an H₂ fraction from said reformate containing residual sulfur in the form of H₂S; and recycling said H₂ fraction to said second desulfurizing zone as said recycled hydrogen.

8. The process of claim 7 wherein said metal comprises essentially iron in particulate form.

9. The process of claim 7 wherein said metal comprises essentially copper in particulate form.

10. The process of claim 7 wherein said metal comprises essentially silver dispersed on a porous refractory support.

11. The process of claim 7 in which said desulfurizing agent comprises bauxite.

12. The process of claim 7 wherein the sulfur content of the feed stock is reduced to the extent of at least 80% in first said desulfurizing zone and wherein at least 70% of the sulfur in the combined feed and recycle streams is removed in said second desulfurizing zone.

13. The process of claim 7 wherein the pressure in said first desulfurizing zone is low and the pressure in the second desulfurizing zone is of the order of 600 p.s.i.a.

14. A process for reducing the sulfur content of a hydrocarbon feed containing at least 0.05 weight percent sulfur which comprises contacting said feed and reducing the same to below 0.003 weight percent, thereby reducing the corrosion effect of said feed in a first desulfurizing zone

with a solid, particulate desulfurizing agent so as to remove at least 80 percent of said sulfur and thereafter contacting the partially desulfurized feed in a second desulfurizing zone with a sulfur accepting metal under metal sulfide-forming conditions including a temperature in the range of 500° to 600° F. so as to remove at least 70 percent of the remaining sulfur therein and reducing the same to below 0.003 weight percent, thereby reducing the corrosion effect of said feed.

10 15. The process of claim 14 wherein said metal comprises essentially particulate iron.

16. The process of claim 14 wherein said metal comprises essentially copper.

15 17. The process of claim 14 wherein said metal comprises essentially silver dispersed on a porous refractory support.

20 18. In a process for reforming a gasoline boiling range hydrocarbon stock containing a minor but substantial amount of sulfur comprising the steps of contacting said stock in a desulfurizing zone with a solid particulate desulfurizing agent so as to reduce the sulfur content to not more than 0.010 weight percent; removing light ends including resulting H₂S from said stock; reforming the remaining stock in admixture with free hydrogen in a catalytic reforming zone so as to produce an improved reformate; recovering an H₂ fraction containing H₂S formed in said reforming zone from said reformate; and recycling said H₂ fraction to said reforming zone without sulfur removal whereby the residual sulfur from the desulfurizing step and recycling of same in said H₂ fraction results in excessive corrosion of metal in said reforming zone: the improvement comprising passing said remaining stock, together with said H₂ fraction, to a second desulfurizing zone in contact with a readily sulfidable metal

25 30 35 and forming metal sulfide therein so as to reduce the sulfur content of the feed stock to said reforming zone not more than 0.003 weight percent of said feed stock before passing same to the reforming step.
